EXTENSION LADDER

John L. Painter, Jr., West Newton, Pa.

Application April 26, 1946, Serial No. 665,177

2 Claims. (Cl. 228—65)

1

My invention relates to improvements in extension ladders, the primary object in view being to provide an extension ladder of all metal construction, to conserve wood, and which is light in weight, yet strong, inexpensive to manufacture, and equipped with easily operative pull means for extending the ladder adapted for locking the same extended or contracted when relieved of pull thereon.

Other and subordinate objects, also comprehended by my invention, together with the precise nature of my improvements and the manifold advantages thereof will be readily understood when the succeeding description and claims are read with reference to the drawings accompanying and forming part of this specification.

In said drawings:

Figure 1 is a view in front elevation of my improved extension ladder, in a preferred embodiment thereof, showing the same extended,

Figure 2 is a view in side elevation, partly broken away,

Figure 3 is a fragmentary view in perspective of the extension section,

Figure 4 is a fragmentary view in longitudinal section taken on the line 4—4 of Figure 1,

Figure 5 is a view in longitudinal section taken on the line 5—5 of Figure 2 and drawn to an enlarged scale,

Figure 6 is a fragmentary view in perspective of the main or base section,

Figure 7 is a fragmentary view in horizontal section taken on the line 7—7 of Figure 5, and

Figure 8 is a fragmentary view in vertical section taken on the line 8—8 of Figure 5.

Reference being had to the drawings by numerals, my improved extension ladder, as shown, comprises a main, or base, section 1 including laterally spaced, parallel, side members 2 of channel iron form, and any suitable light strong metal. The side members 2 on the confronting, or inner side faces thereof are formed with front and rear right angled edge flanges 3, 4 confronting to form therebetween longitudinal slots 5 in the inner side faces of the members extending centrally thereof from end to end of the same. The side members 2 function as guides for an extension section 6, to be described.

Rungs 7 of T-iron form are welded, or otherwise secured, as at 8, at their ends to the rear flanges 4, and are spaced apart vertically with the usual spacing therebetween and with flat sides uppermost so that said rungs are of step-like form. As will be seen, the rungs 7 are arranged in the rear of the longitudinal center of the main

2

section 2 and in the rear of the slots 5. The purpose of this arrangement will presently be clear. As best shown in Figure 8, the rungs 7 are arranged so that the uppermost flat sides thereof incline toward the front of the main section 1 so that when said section is inclined upwardly and rearwardly, the uppermost flat sides of the rungs will be positioned substantially horizontally to provide approximately level steps, with the main section 1 arranged at the necessary inclination.

The extension section 6 includes side members 9 vertically slidable in the side members 2 of the base section 1 and constructed in the same manner as said members 2 with the exception that the outer side faces of said members 9 are formed with the longitudinal central slots 10 corresponding to the slots 5 of said members 2. The rungs 11 of the extension section 6 are constructed and arranged in the same manner as the rungs 7 of the main section 1 with the exception that said rungs 11 are secured to the side members 9 in the longitudinal centers of said members so that said rungs 11 may pass into and out of the slots 5 in the side members 2, and slightly forwardly of the rungs 7.

For sliding the extension section 6 outwardly and inwardly relative to the base section 1 to extend and contract the ladder, respectively, the following means is provided.

A pull line, preferably in the form of a flat tape 12 is extended slidably through a ring 13 swivelled, as at 14 on the top rung 7 of the base section 1 in the transverse center of said rung and so that said tape provides a pendent free hand-grip portion 15 and an attaching end 16 both, preferably, in front of the rungs 7 and 11. The attaching end 16 is secured, as at 17, to the center portion of a flexible wire pull member 18 slidably extended upon opposite sides of its center downwardly through a tubular guide 19 of inverted V-shape suitably secured by a flange 20 to a rung 11 of the extension section 6 in the transverse center of said section. From the guide 19, the member 18 inclines downwardly to a pair of tubular upwardly curved guides 21 suitably fixed on top of the rung 11 immediately below the rung 11 to which said guide 19 is fixed, said guides 21 being arranged to extend into the slots 5 of the side members 2 at opposite ends of the rung 11 on which the same are fixed. At the terminals thereof, said member 18 is suitably attached, as represented, for instance, at 22 to the inner ends of a pair of latch bolts 23 slidably extended through the inner side faces of the side mem-

bers 9 and spring loaded, as at 24 to be projected outwardly into vertically spaced apertures 25 provided in the outer side faces of the side members 2 of the base section 1. Collars 26 on the latch bolts 23 slidably fitted in suitable guide bushings 27 on the side members 9 guide said latch bolts in projection and retraction thereof and by engagement with the outer side faces of the side members 2 limit projecting movement of said latch bolts. The bushings 27, as will be understood, are arranged to play vertically in the slots 5 of the side members 2. The apertures 25 are vertically spaced in correspondence with the spacing of the rungs 7, and 11 but slightly above rungs 7 of the base section 1 so that when the latch bolts 23 enter said apertures 25, the rungs 11 of the extension section 6 which are positioned between the side members 2 of the base section 1 will be slightly higher than the rungs 7 of said base section. This is to provide for spacing the instep portion of the feet on top of such rungs 11 without interference by the adjacent rungs 7.

The manner in which the described ladder is extended and contracted will be readily understood. By pulling on the hand-grip portion 15 of the tape 12, with the ladder in proper position, a pull may be exerted on the member 18 to retract the latch bolts 23, in opposition to the springs 24, out of apertures 25 into which they may have been projected. Thus the extension section 6 is unlocked, or unlatched, from the main section 1 for sliding inwardly or outwardly of said main section. By continuing the pull on the hand-grip section 15, the latch bolts 23 will be stopped in fully retracted positions as the collars 26 fully compress the springs 24, at which point, the extension section 9 will be pulled outwardly of the base section 1. When the extension section 9 has been extended to the desired position, the hand-grip portion 15 of the tape 12 may be released and the extension section held by hand until the latch bolts 23 are projected by the springs 24 into the appropriate apertures 25 to lock the extension section 9 in selected extended position. By easing up on the pull on the hand-grip portion 15 of the tape 12 sufficiently to permit the extension section 9 to move inwardly of the base section 1 (under the influence of gravity), the ladder may be contracted to a desired extent and the extension section 6 locked, or latched, to the main section 1 in the same manner as described with reference to extending the ladder.

The foregoing will, it is believed, suffice to im-

part a clear understanding of my invention without further explanation.

Manifestly, the invention, as described, is susceptible of modification without departing from the inventive concept, and right is herein reserved to such modifications as fall within the scope of the appended claims.

What I claim is:

1. Operating means for an extension ladder having rung connected inner channel side members slidably fitting with the bottoms of the channels confronting in outer channel side members, said means comprising a pair of opposite bushings fixed in the channels of the inner side members in hidden position, spring loaded latch bolts slidably retractile in said bushings and extending out of said bottoms, a pair of upwardly curved tubular guides on one rung opposite said latch bolts, a flexible pull member of inverted V-shape extending upwardly from said guides with ends extending into said guides and attached to said latch bolts, a tubular guide on a higher rung into which said flexible member extends, and a pull line attached to said flexible member to extend upwardly from said last named guide.

2. Operating means according to claim 1 wherein said last named tubular guide is of inverted V-shape.

JOHN L. PAINTER, JR.
